UNITED STATES PATENT OFFICE.

JEREMIAH HALL, OF SHELL ROCK, IOWA.

IMPROVEMENT IN HARVESTERS.

Specification forming part of Letters Patent No. **156,344**, dated October 27, 1874; application filed March 10, 1874.

To all whom it may concern:

Be it known that I, JEREMIAH HALL, of Shell Rock, in the county of Butler and State of Iowa, have invented certain new and useful Improvements in Harvesters; and I do hereby declare the following to be a full, clear, and exact description thereof, reference being had to the accompanying drawing and to the letters of reference marked thereon.

The nature of my invention consists principally, first, in a device for conveying the grain as it falls on the harvester-platform to a receptacle formed at the inner end of the platform; second, in a device for lifting the grain from the receptacle in parcels of suitable size for bundles and placing them on the binding-table.

In order to enable others skilled in the art to which my invention appertains to make and use the same, I will now proceed to describe its construction and operation, referring to the annexed drawing, which forms a part of this specification, and in which—

Figure 1 is a plan view of a harvester embodying my invention. Fig. 2 is a rear elevation of the same. Fig. 3 is a side view of one of the cams used to operate the lifting device. Fig. 4 is a detailed view of the reciprocating conveying-carriage. Fig. 5 is a sectional view.

A represents the frame of my machine supported at the inner end by the large driving or master wheel B, and at the outer end by a smaller wheel, B', which may be made adjustable up and down, as is done in some harvesters. Over the inner end of the frame is erected a vertical frame-work, C, in which is secured the binders' table D, directly over the master-wheel B. E represents the platform of the harvester, which is slotted longitudinally, as shown in Fig. 1, and from the inner end of the platform extends a concave longitudinally-slotted addition or extension of the platform upward to the edge of the binders' table, which forms a receptacle, G, wherein the grain is collected to form a suitably-sized bundle, and is then carried up to the top of the binders' table. On the inner side of the main driving or master wheel B is attached a cog-wheel, H, which gears with a pinion, a, on the end of a short shaft, b, running on a line in rear of and

parallel with the axle of the driving-wheel. On the shaft b is a miter-wheel, d, which gears with a corresponding pinion, e, on the front end of the shaft f running at right angles with the former shaft. On the rear end of the shaft f is a crank, i, from which a pitman, I, connects with the rear end of a lever, J, pivoted in the frame A. The front end of this lever is pivoted to the cutter-bar K and operates the same by the oscillating motion imparted to it by the crank and pitman above described. On the shaft f, at or near the rear end, is a pinion, h, gearing with a cog-wheel, k, on a shaft, h'. The cog-wheel k is permanently secured on the shaft h', so that this shaft will always revolve when the shaft h revolves. On the end of the shaft h' is a crank, i', connected by a pitman, I', with a lever, J', pivoted in the frame A; and the front end of this lever is, by a rod, m, connected with a carriage, L, located under the platform E, so that, by the revolutions of the crank i', said carriage obtains a reciprocating motion. The carriage L consists simply of two parallel side bars connected by suitable cross-bars and sliding in grooves made in the longitudinal bars of the frame A under the platform E. In the carriage is a series of shafts, p p, each provided with a number of curved teeth, n n. Upon one end of each shaft p is a crank, s, with projecting pin inserted in a hole, t, in a bar, M, placed at the side of and moving with the carriage. At each end of the path of the carriage L is a bumper, v, so arranged that the end of the bar M will strike the same an instant before the carriage completes its stroke.

When the carriage reaches the end of its track, near the receptacle G, the bar M, having been stopped by the bumper an instant before, causes the shafts p p to turn so as to throw the teeth n n down below the surface of the platform, where they remain during the passage of the carriage to the opposite end of the track. At this end, in like manner, by the stoppage of the bar M before the carriage is stopped, the teeth n n are thrown up through the slots of the platform, and are held in this position by friction, or a spring, or other suitable means during the return of the carriage, and carry the grain with them to the receptacle G. On the shaft h' above described is a

loosely-fitting pinion, w , which is revolved with the shaft by means of a clutch, x , feathered on the shaft. This pinion w gears with a cog-wheel, N , upon the end of a shaft, y , which passes through the frame-work C below and parallel with the binders' table D . On the inner side of the cog-wheels are two cams or cam-grooves a' and b' for operating the lifter.

The grooves a^1 and b^1 give motion to two levers, O and O ^{2} , and a groove, a^2 , on the inner side of a wheel, N', upon the other end of the shaft y, gives motion to a lever, O ^{1} . The grooves a^1 a^2 for operating the levers O O ^{1} correspond with each other in form. All the levers O O ^{1} O ^{2} move on fulcrums firmly attached to the frame C. Each lever has a projecting pin on its inner or short end with a roller upon it to work in its cam groove and receive the pressure of the cams and transmit their motion to the levers. In the outer ends of the levers O O ^{1} a shaft, P, has its bearings, and to this shaft are attached the fingers Z Z for lifting the grain up. The outer end of the lever O ^{2} is connected by a rod, d^1 , with an oscillating stay, d^2 , which is pivoted on the same fulcrum as the lever O, and this stay is by a rod, d^3 , connected with a crank, d^4 , on the end of the shaft P. To lift the grain from the receptacle G and place it on the binding-table D, the ends of the fingers Z are brought down to the inner end of the platform of the harvester, when the cam-wheel N presses out the short arm of the lever O ^{2} , thus driving back the connecting-rods d^1 d^2 the upper end of the stay d^2 and the crank d^4 , thus causing the shaft P to make part of a revolution until the fingers Z reach a horizontal position or thereabout, when the cam-wheels N N' press down the short arms of the levers O O ^{1} , carrying up the other ends with the shaft P, during which motion the cam-wheel N so presses back the lever O ^{2} and turns back the shaft P that the ends of the fingers remain nearly stationary, while the shaft is being carried up till it reaches a sufficient height to empty the grain carried up by the fingers on the table D, and then after the cam-wheels have made part of a revolution without moving the fingers or either of the levers, the cam-wheel N still further turns back the shaft P and throws back the lower ends of the fingers till they stand in nearly a perpendicular position, when the long arms of the levers O O ^{1} are again brought down, bringing with them the shaft P and the lower ends of the fingers to their starting point at the inner end of the platform E.

D¹ represents the platform or foot board, upon which the binder stands. Convenient to this foot-board and pivoted to the frame C is a treadle, R, connected by a rod, e', with one arm of an elbow-lever, S. This lever is pivoted at its angle to the frame C, and at the end of its other arm is a loop, f', through which passes one end of a pivoted lever, m'. The other end of this lever is forked and fits

in a circumferential groove on the clutch X. This clutch is held against the pinion w by a spring, n' .

By depressing the treadle R with the foot the clutch X is thrown out of gear, hence the shaft h' will revolve without turning the pinion w , and thus stop the motion of the grain-lifting apparatus without interfering with the movement of the cutter-bar and grain-carrier, the object being to allow the grain to accumulate in larger quantities in the receptacle G before it is taken up by the fingers.

To enable the driver to do the work of distributing the bundles in convenient position for setting up on the field, I arrange at the side of and near the rear end of the binder's table a carrying-table, D^2 , pivoted or hinged to an arm, p' , and operated by means of a compound lever, consisting of two bent levers, s^1 and s^2 , united at t' . The lower end of the lever s^2 is attached to the carrying-table D^2 , and the forward end of the lever s^1 is in position to be worked by the driver. In the lower arm of the lever s^2 is a joint, v' , which admits of its bending outward, when the forward end of the lever s^1 is drawn back and tilting the table, but prevents it, after the end of the lever s^1 is thrown forward, from bending any further inward, and thereby it forms a self-adjusting lock to prevent the table from being tilted by the weight of the bundles.

It will be seen that this harvester is designed to save the labor of one binder. This is accomplished by delivering the grain on the binding-table in parcels of suitable size for binding, where it is bound without removal to another place, thus permitting the binder to stand in the same position and do his work, and not consume his time in passing from one place to another. All this is secured by placing the binding-table directly over the master-wheel, as above described. It also relieves the binder from the labor and care of distributing the bundles upon the field by enabling the driver to do that work,

Having thus fully described my invention, what I claim as new, and desire to secure by Letters Patent, is—

1. The combination with the carriage L, shafts p , and teeth n of the cranks s , sliding perforated bar M and bumpers v , all constructed substantially as and for the purposes herein set forth.
  2. The combination of the cam-wheels N N', levers O O¹ O², rods $d^1 d^3$, stay d^2 , and crank d^4 , all constructed as described, to operate the shaft P with its fingers f , in combination with the receptacle G, substantially as and for the purposes herein set forth.

In testimony that I claim the foregoing as my own I affix my signature in presence of two witnesses.

JEREMIAH HALL.
